MACHINE FOR CUTTING SHOE TREEING STICKS

Paul H. Dixon, Swampscott, Mass., assignor to United Shoe Machinery Corporation, Borough of Flemington, N. J., a corporation of New Jersey

Application February 1, 1938, Serial No. 188,112

2 Claims. (Cl. 12—1)

This invention relates to machines for cutting shoe treeing sticks, and particularly to a machine for cutting treeing sticks each to a length suitable for insertion in an individual shoe.

5 In the manufacture of women's shoes and slippers, after the lasts have been removed it is customary to insert a stick of resilient material such as rattan between the tip and the counter to hold the shoe or slipper in shape. The strips 10 are slightly longer than the distance between the tip and the counter so that they are bent when placed between these members, thereby being placed under tension and as a result will prevent the sole of the shoe from turning up. In order 15 that the stick may function efficiently as a shoe tree it must be properly proportioned to the length of the shoe in which it is to be used. However, as these sticks are supplied to the manufacturers in lengths which are too long for the 20 shoes in which they are to be used and as the lengths vary with different styles and sizes the sticks must be individually cut for the shoe in which they are to be used.

It is an object of this invention to provide a 25 machine for cutting shoe treeing sticks which, in combination with the shoe to be treed, will enable the operator to determine readily the proper length of stick for that particular shoe and to cut the stick to that length forthwith. To this end, and as illustrated, the machine provides a frame having a knife slidably mounted therein and means thereon for engaging a shoe when presented to the machine and holding the rear portion thereof a determined distance from 30 the knife whereby the latter may sever the projecting portion of a treeing stick at a fixed distance from the counter.

These and other features of the invention will 35 appear more fully in the following detailed description when read in connection with the accompanying drawing and will be pointed out in the appended claims.

Fig. 1 is a front view of the machine embodying this invention; and

40 Fig. 2 is a sectional view taken along line II—II of Fig. 1 and illustrates a shoe in operative position relatively to the knife.

The illustrated machine comprises a frame 10 having a rectangular recess formed in the head thereof in which is slidably mounted a plunger 12. Attached to the front face of the head is a guide plate 14 having a cutting blocks 16 fastened to the inner face thereof, the cutting block being received in a channel 18 formed in the upper portion of the plunger 12. The top of the cutting block has formed thereon a knife 20 which is arranged to cooperate with a knife 22 attached to the plunger 12 at one side by an

extension 24 formed on the plunger. The knife 22 is open at one side so that long reeds or sticks may be inserted sideways from the open side. The adjoining surfaces of the knives 20 and 22 are made convex and concave respectively in order that the severed face of the treeing stick which is to engage the counter will be rounded so as not to damage the shoe.

The upper portion of the front face of the guide plate 14 has a heel seat 25 formed therein for engagement with the rear portion of a shoe and thus to hold the heel spaced from the knives, as shown in Fig. 2, thereby controlling the point at which the stick will be severed. The slideable blade 22 is moved downwardly by a rod 26 fastened at one end to the plunger 12 and connected at its opposite end to a treadle-lever 28 pivotally mounted on a base 30. The plunger 12 and blade 22 are biased in an upward direction by a spring 32 surrounding the rod 26 and held 15 between a plate 34 which engages a table 36 and a collar 36 fastened to the rod 26.

The treeing sticks are cut each to an appropriate length in the following manner. A stick such as 38 is first inserted in a shoe so that one end will engage the tip thereof, as shown in Fig. 2, with the opposite end portion extending outwardly over the edge of the counter portion of the shoe. Then the shoe is presented to the machine heel first, so that the heel will be received in the seat 25. When in this position the 30 projecting portion of the resilient stick 38 will lie between the knife blades where it may be severed by the operation of the treadle-lever 28.

Having described my invention, what I claim 35 as new and desire to secure by Letters Patent of the United States is:

1. A machine for cutting shoe treeing sticks comprising a fixed knife, a work locating member extending along one side of the knife and having a curved seat adapted to engage and position the counter portion of a shoe in spaced relation to the edge of the knife, and a movable knife on the other side of the fixed knife and cooperable therewith to sever the treeing stick at a predetermined distance beyond the counter portion of the shoe.

2. A machine for cutting shoe treeing sticks comprising a fixed knife and a movable knife having curved cutting edge portions cooperable to sever a treeing stick projecting from a counter portion of a shoe presented to the machine, and a work locating member adjacent to the knives and having a curved seat constructed and arranged to engage the counter portion of the shoe to position it in predetermined spaced relation to the cutting edge portions of the knives.

PAUL H. DIXON.
